UNITED STATES PATENT OFFICE

WILLIAM L. MCGRATH, OF ELMIRA, NEW YORK, ASSIGNOR TO ECLIPSE MACHINE COMPANY, OF ELMIRA HEIGHTS, NEW YORK, A CORPORATION OF NEW YORK

ENGINE STARTER

Application filed September 4, 1925. Serial No. 54,433.

My invention relates to an engine starter, and pertains more particularly to the drive or transmission between a prime mover such as an electric motor and a member of the engine to be started such as the flywheel thereof. The drive in which my invention is embodied is of the radial shift type in which a rotatable member or pinion which is adapted to transmit the torque of the starting motor of the prime mover or starting motor is positioned in the plane of the engine member and adapted to be brought into operative engagement or mesh with such engine member at the time of the cranking operation.

The object of my invention is to provide a drive or transmission of this type which shall be simple in construction and efficient in operation and containing advantages in functioning and results which will be apparent from the description hereinafter given.

In the drawings, Fig. 1 is a sectional elevation of an engine starter incorporating my invention; Fig. 2 a sectional elevation on the line 2—2 of Fig. 1 but omitting the motor; and Fig. 3 a sectional elevation similar to Fig. 2 but showing one side of the swinging frame removed and showing the drive in operative relation with the flywheel of the engine.

Referring to the particular embodiment of my invention as herein shown, the prime mover is here in the form of an electric starting motor 1 and the drive is of the direct type and accordingly the armature shaft 2 of the motor is extended and the drive or transmission is mounted thereupon and driven thereby.

The drive includes a rotatable member which is here in the form of a sleeve 3 which is mounted upon the armature shaft and operatively connected therewith, preferably in a yielding manner as by means of the drive spring 4. This drive spring is connected at its opposite ends with the drive head 5 secured to the armature or power shaft 2 by means of the bolt 6 and to the drive head portion 7 of the screw shaft by means of the bolt 8. This sleeve has a screw

threaded portion 9 and a smooth portion 10 and the same is provided at its inner end adjacent the motor with an abutment or stop nut 11. A driving member which is in the form of a pinion 12 is loosely mounted upon the said smooth or plain portion of the shaft which portion is located between said abutment and the screw threaded portion of the sleeve. A screw member or nut 13 is threaded upon the screw threaded portion of the sleeve for longitudinal movement to the right (Fig. 1) when the shaft and sleeve are rotated, to thereby engage the left hand face of the pinion 12 and clamp such pinion against the abutment to thereby drivingly connect the pinion with the sleeve. The normal position of the screw member or nut 13 is at the outer ends of the screw threads and away from the pinion 12 as shown in Fig. 1.

A frame is mounted to swing or oscillate with the axis of the motor armature as a center and in the present instance, such frame is mounted upon the pinion 12. To this end, the frame comprises two parallel plates 14 having at their upper end an opening to receive opposite sides of the periphery of the pinion 12. As shown in Figure 1, the pinion teeth do not extend all the way across the body of the pinion, but are cut away at their opposite ends and such body portion is also recessed as at 15 in order to provide peripheral bearings for these plates 14. These plates are held together in proper spaced relationship by means of the bolts 16. In the lower portion of the frame, there is journaled a second or transmitting pinion 17 loosely mounted upon a center shaft 18 which is preferably provided with a bushing 19. The parts are held in place by means of another bolt 20.

The pinion 17 is constantly in mesh with the driving pinion, but is normally out of mesh or driving relationship with the engine member or gear, such as the flywheel indicated at 21. This normal position of the drive is indicated in Fig. 2, but upon the operation of the starting motor the pinion 17 will automatically swing to the left and intermesh with the flywheel, as shown in

Fig. 3, as an incident to and the result of the transmission of torque through the driving pinion 12.

Describing a cycle of operation of the parts and beginning with the same in their normal position, shown in Figs. 1 and 2, when it is desired to crank the engine, the starting motor 1 is energized with the result that its armature shaft and the screw sleeve 10 are rotated in a clockwise direction as indicated by the arrow in Fig. 3. This rotation of the sleeve causes a longitudinal movement of the screw member or nut 13 to the right and against the left-hand face of the driving member or pinion 12. This causes a clamping of such pinion against the abutment 11 and clamps such pinion in driving relationship with the screw sleeve. The driving pinion 12 thereupon starts to rotate 15 with the sleeve and as it is constantly in mesh with the transmitting pinion 17, such pinion will be swung to the left (Fig. 3) and into mesh with the flywheel, as shown in Fig. 3. So long as the torque is being transmitted from the starting motor to the engine, the transmitting pinion will remain in mesh and will rotate the flywheel and crank the engine. When the engine starts and operates under its own power, the excess speed 20 of rotation of the flywheel transmitted from pinion 17 to pinion 12 will cause the nut 13 to be rotated faster than it is being rotated by the screw sleeve, with the result that the nut will be moved to the left (Fig. 1) 25 and the pinion 12 will be unclamped so that it will be free and unable to transmit torque in either direction. Thereupon, the entire frame and the transmitting pinion 17, being thus free, will swing away from the flywheel 30 back to normal position as shown in Fig. 2, and will remain in that position, in this instance, by gravity, until the next starting operation. My construction thus avoids the use of complicated mechanism intended 35 to insure and maintain disengagement of the pinion from the flywheel gear after the engine has started.

I claim:

1. In an engine starter drive of the radial shift type, the combination with a rotatable member of the engine to be started, of a rotatable driving shaft, a rotatable driving member normally loosely mounted thereon, means actuated automatically by the rotation of such driving shaft for operatively connecting the driving member to the driving shaft when the latter is rotated, and a rotatable member constantly in operative relationship with the driving member and normally out of operative relationship with the engine member, but mounted to swing into such operative relationship by the torque transmitted through the driving member and being constantly free to swing into

and out of such relationship according to direction of torque application thereto.

2. In an engine starter drive of the radial shift type, the combination, with a rotatable member of the engine to be started, of a rotatable driving shaft, a rotatable driving member normally loosely mounted thereon, means actuated automatically by the rotation of such driving shaft for operatively connecting the drive member to the driving shaft when the latter is rotated, a swinging frame carried by such driving member, and a rotatable member journaled in such frame and constantly in operative relationship with the driving member and normally out of operative relationship with the engine member but adapted to swing into such operative relationship by the torque transmitted through the driving member and constantly free to swing into or out of such operative relationship according to direction of torque application thereto.

3. In an engine starter drive of the radial shift type, the combination, with a rotatable member of the engine to be started, of a rotatable driving shaft, a rotatable driving member normally loosely mounted thereon and rotatable in a fixed plane, means actuated automatically by the rotation of such driving shaft for clamping the driving member to the driving shaft when the latter is rotated, such means comprising a clamping device mounted on the shaft for longitudinal movement therealong when such shaft is rotated and into clamping engagement with said driving member, and a driving connection between the driving member and the engine member which connection is swung radially by torque applied to said driving member.

4. In an engine starter drive of the radial shift type, the combination, with a rotatable member of the engine to be started, of a rotatable driving shaft, a rotatable driving member normally loosely mounted thereon and rotatable in a fixed plane, means actuated automatically by the rotation of such driving shaft for clamping the driving member to the driving shaft when the latter is rotated, said shaft having external screw threads and such means comprising a screw member threaded on said threads of the shaft for longitudinal movement along the shaft and into clamping engagement with said driving member to rotarily connect the latter to the shaft, and a driving connection between the driving member and the engine member which connection is swung radially by torque applied to said driving member.

5. In an engine starter drive of the radial shift type, the combination, with a rotatable member of the engine to be started, of a rotatable driving shaft, a rotatable driving member normally loosely mounted thereon and rotatable in a fixed plane, means actu-

ated automatically by the rotation of such driving shaft for clamping the driving member to the driving shaft when the latter is rotated, said shaft having external screw 5 threads and such means comprising a screw member threaded on said threads of the shaft for longitudinal movement along the shaft and into clamping engagement with said driving member to rotarily connect the 10 latter to the shaft, and a driving connection constantly in driving relationship with said driving member and mounted to swing into driving relationship with the engine member when the driving member transmits torque 15 and by means of that torque.

6. In an engine starter drive of the radial shift type, the combination, with a rotatable member of the engine to be started, of a rotatable driving shaft, a rotatable driving 20 member normally loosely mounted thereon and rotatable in a fixed plane, means actuated automatically by the rotation of such driving shaft for clamping the driving member to the driving shaft when the latter is 25 rotated, said shaft having an abutment on one side of the driving member, said means comprising a clamping device located on the other side of the driving member and adapted to clamp the latter against said abutment 30 to drivingly connect the driving member to the shaft, and a driving connection between the driving member and the engine member.

7. In an engine starter drive of the radial shift type, the combination, with a rotatable member of the engine to be started, of a rotatable driving shaft, a rotatable driving member normally loosely mounted thereon and rotatable in a fixed plane, means actuated automatically by the rotation of such 40 driving shaft for clamping the driving member to the driving shaft when the latter is rotated, said shaft having an abutment on one side of the driving member, said means comprising a clamping device located on the 45 other side of the driving member and adapted to clamp the latter against said abutment to drivingly connect the driving member to the shaft, and a driving connection constantly in driving relationship with said 50 driving member and mounted to swing into driving relationship with the engine member when the driving member transmits torque.

8. In an engine starter drive of the radial shift type, the combination, with a rotatable member of the engine to be started, of a rotatable driving shaft, a rotatable driving member normally loosely mounted thereon and rotatable in a fixed plane, means actuated automatically by the rotation of such driving shaft for clamping the driving member to the driving shaft when the latter is rotated, said shaft having exterior screw threads on one side of the driving member 65 and an abutment on the other side thereof,

said means comprising a screw member threaded upon said screw threads for longitudinal movement to clamp the driving member against the abutment and thereby drivingly connect the driving member to the shaft, and a driving connection between the driving member and the engine member. 70

9. In an engine starter drive of the radial shift type, the combination with a gear of the engine to be started, of a rotatable driving shaft, a driving pinion normally loosely mounted thereon, means actuated automatically by the rotation of the driving shaft for operatively connecting the pinion to the shaft in driving relationship when such shaft is rotated, and a transmitting pinion between the driving pinion and the engine gear, such transmitting pinion being shifted radially by the torque transmitted through the driving pinion and being constantly free to be shifted radially in either direction according to direction of torque application thereto. 75

10. In an engine starter drive of the radial shift type, the combination with a gear of the engine to be started, of a rotatable driving shaft, a driving pinion normally loosely mounted thereon, means actuated automatically by the rotation of the driving shaft for operatively connecting the pinion to the shaft in driving relationship when such shaft is rotated, and a second pinion constantly meshing with the driving pinion and constantly located in the plane of the engine gear, said second pinion being shiftable radially into engagement with the engine gear by the torque transmitted through the first said pinion and being constantly free to be shifted radially in either direction according to direction of torque application thereto. 80

11. In an engine starter drive of the radial shift type, the combination with a gear of the engine to be started, of a rotatable driving shaft, a driving pinion normally loosely mounted thereon, means actuated automatically by the rotation of the driving shaft for operatively connecting the pinion to the shaft in driving relationship when such shaft is rotated, a swinging frame mounted on said driving pinion, and a second pinion mounted in such frame and constantly in mesh with the driving pinion, such second pinion being constantly free to be shifted radially in either direction according to the direction of torque application thereto and adapted to mesh with the engine gear when swung thereinto by the torque applied to the first pinion and to rotate said engine gear. 105

12. In an engine starter drive of the radial shift type, the combination with a gear of the engine to be started, of a power shaft, a sleeve mounted on the shaft and rotatably connected therewith, a pinion constantly concentric with the sleeve and normally 110 120 125 130

- loosely mounted on the sleeve to rotate in a fixed plane, a screw member threaded on the sleeve for longitudinal movement thereon to clamp the pinion thereto; and a driving connection between the pinion and the engine gear.
13. In an engine starter drive of the radial shift type, the combination with a gear of the engine to be started, of a power shaft, a sleeve mounted on the shaft and rotatably connected therewith, a pinion normally loosely mounted on the sleeve to rotate in a fixed plane, a screw member threaded on the sleeve for longitudinal movement thereon to clamp the pinion thereto, and a second pinion constantly meshing with the first pinion and normally out of mesh with the engine gear but mounted to swing into mesh with such gear when the first pinion is clamped to the sleeve.
14. In an engine starter drive of the radial shift type, the combination with a gear of the engine to be started, of a power shaft, a sleeve mounted on the shaft and rotatably connected therewith, a pinion normally loosely mounted on the sleeve to rotate in a fixed plane, a screw member threaded on the sleeve for longitudinal movement thereon to clamp the pinion thereto, a frame pivotally mounted upon the pinion, and a second pinion journaled in such frame and constantly in mesh with the first pinion and normally out of mesh with the engine gear but adapted to be swung into mesh therewith when the first pinion is clamped to the sleeve.
15. In an engine starter drive of the radial shift type, the combination with a gear of the engine to be started, of a power shaft, a sleeve mounted on the shaft, a yielding driving connection between the shaft and sleeve, said sleeve having a plain portion and a screw threaded portion, a pinion loosely mounted on said plain portion to rotate in a fixed plane, a nut threaded on the screw threaded portion for longitudinal movement against the pinion to clamp it drivingly to the sleeve when the shaft and sleeve are rotated, and a second pinion connecting between the first pinion and the engine gear.
16. In an engine starter drive of the radial shift type, the combination with a gear of the engine to be started, of a rotatable driving shaft, a driving pinion normally loosely mounted thereon, means actuated automatically by the rotation of the driving shaft for clamping the pinion to the shaft in driving relationship when such shaft is rotated, a frame mounted directly on the body of the pinion to swing upon the pinion, and a second pinion journaled in such frame and constantly in mesh with the driving pinion but adapted to mesh with the engine gear when swung thereinto and to rotate the same.
17. In an engine starter drive of the radial shift type, the combination with a gear of the engine to be started, of a rotatable driving shaft, a driving pinion normally loosely mounted thereon, means actuated automatically by the rotation of the driving shaft for coating directly with the side face of said pinion to clamp the pinion to the shaft in driving relationship when such shaft is rotated, the periphery of the body of such pinion on its opposite sides being formed with annular bearing surfaces, a frame mounted to swing upon such surfaces of the pinion, and a second pinion journaled in such frame and constantly in mesh with the driving pinion but adapted to mesh with the engine gear when swung thereinto and to rotate the same.
18. In an engine starter drive of the radial shift type, the combination, with a rotatable member of the engine to be started, of a rotatable driving shaft, a rotatable driving member normally loosely mounted thereon, a driving connection for operatively connecting between said two members and constantly free to be swung radially for making or breaking such operative connection, and combined means located in the line of transmission of torque for automatically connecting the driving member to the driving shaft and for radially shifting said driving connection into engagement with the engine member by means of the torque so transmitted to the driving member.
19. In an engine starter drive of the radial shift type, the combination, with a rotatable member of the engine to be started, of a rotatable driving shaft, a rotatable driving member normally loosely mounted thereon, a driving connection for operatively connecting between said two members and constantly free to be swung radially for making or breaking such operative connection, and combined means for first automatically connecting the driving member to the driving shaft and for then radially shifting said driving connection into engagement with the engine member by means of the torque transmitted through the driving member.
20. In an engine starter drive of the radial shift type, the combination with a rotatable member of the engine to be started, of a rotatable driving shaft, a rotatable driving member normally loosely mounted thereon, means actuated automatically by the rotation of such driving shaft for operatively connecting said driving member to the driving shaft when the latter is rotated, a driving connection between the driving member and the engine member mounted to stand normally in idle position and to be swung radially into active position by the torque transmitted through said driving member, a source of power, and a yielding

driving connection between said source of power and said rotatable driving shaft.

21. In an engine starter drive of the radial shift type, the combination with a rotatable member of the engine to be started and a source of power, of a rotatable driving shaft, a torsional yielding connection between said driving shaft and said source of power, a rotatable driving member normally loosely mounted on said driving shaft, means on said driving shaft and actuated automatically by the rotation thereof for operatively connecting the driving member to the driving shaft when the latter is rotated, and a rotatable member constantly in operative relationship with the driving member and normally out of operating relationship with the engine member but mounted to swing into such operative relationship by the torque transmitted through the driving member.

22. In an engine starter drive of the radial shift type, the combination with a gear of the engine to be started, of a rotatable drive shaft, a driving pinion normally loosely mounted thereon, means actuated automatically by the rotation of the driving shaft for clamping the pinion to the shaft in driving relationship when such shaft is rotated, a frame mounted directly on the body of the pinion to swing upon the pinion, and a second pinion journaled in such frame and constantly in mesh with the driving pinion but adapted to mesh with the engine gear when swung thereinto and to rotate the same, said driving pinion being constantly located in the plane of the engine gear and said second pinion being constantly free to be shifted radially in either direction according to the direction of torque application thereto.
